CLAIM

The ornamental design for a cookware lid, as shown and
described.

DESCRIPTION

FIG. 1 is a bottom front perspective view of a cookware lid,
according to the present design.

FIG. 2 a top plan view of the cookware lid of FIG. 1.

FIG. 3 is a bottom plan view of the cookware lid of FIG. 1.

FIG. 4 is a cross-sectional front elevation view of the
cookware lid taken in the direction of line 4-4 in FIG. 2.

FIG. 5 is a cross-sectional rear elevation view of the
cookware lid taken in the direction of line 5-5 in FIG. 2.

FIG. 6 is a cross-sectional left side elevation view of the
cookware lid taken in the direction of line 6-6 in FIG. 2; and,
FIG. 7 is a cross-sectional right side elevation view of the
cookware lid taken in the direction of line 7-7 in FIG. 2.

The broken lines shown in the drawings depict portions of
the cookware lid that form no part of the claimed design.
